CLAIM

The ornamental design of a plate with cover, as shown and described.

DESCRIPTION

FIG. 1 is a front perspective view illustrating the plate with cover, constructed in accordance with the teachings of the present invention.

FIG. 2 is a front elevational view of the plate with cover of FIG. 1.

FIG. 3 is a rear elevational view of the plate with cover of FIG. 1.

FIG. 4 is a side elevational view of the plate with cover of FIG. 1.

FIG. 5 is a top plan view of the plate with cover of FIG. 1; and,

FIG. 6 is a bottom plan view of the plate with cover of FIG. 1.
